F. JACHIMSTAL

HINGE FOR STORM SASHES

Filed Nov. 10, 1925

UNITED STATES PATENT OFFICE.

FRED JACHIMSTAL, OF MANITOWOC, WISCONSIN.

HINGE FOR STORM SASHES.

Application filed November 10, 1925. Serial No. 68,141.

The invention relates to hinges and particularly to hinges for securing in position storm sashes on windows and has for its object the provision of means for hinging 5 storm windows by which the storm sash may be installed in the window frame and removed therefrom by manipulation from the inside of the building and comprises hinge members including socket members adapted 10 to be secured to the outside of the window frame and grating members adapted to be secured to the outer side of the storm sash, one of said members on the sash being provided with a fixed stud to engage in a socket 15 on the frame, and the other member provided with a spring projected bolt to engage in the other socket on the frame, said member being also provided with means for retracting the bolt by manipulation from 20 the inside of the storm sash so that the sash may be installed or removed, as stated, from the inside of the building.

The invention will be described in detail hereinafter and will be found illustrated in 25 the accompanying drawings, in which

Figure 1 is a view of the upper fragment of a window frame and storm sash showing the improved hinges in position,

Figure 2, a similar view showing the hinge 30 members partly in section,

Figure 3, a vertical sectional view on a plane indicated by the line 3—3 of Figure 1, and

Figure 4 is a horizontal, fragmental sectional view on a plane indicated by the line 35 4—4 of Figure 1.

In the drawings, similar reference characters will be used to designate corresponding parts throughout the several views.

As heretofore stated the invention is designed to provide means by which storm sashes may be installed and removed from the window frame by manipulation from the interior of the building, and in the drawings 45 the window frame is indicated at A, and the storm sash at B. The hinge members, that are the subject matter of the invention, comprises socket members 1, adapted to be secured to the window frame A, and having sockets 2 with cylindrical bores.

Secured to the storm sash B are the mating members of the hinges. One of these members is shown at 3 and is provided with a fixed stud or pin 4 and adapted to engage

in one of the sockets 2. The other hinge member designated 5 is provided with a cylinder 6 in which is slidably mounted a cylindrical bolt 7 having a stem 8 that extends through an opening in the end of the cylinder 6 and is provided also with a longitudinal slot 9 adjacent the outer end of the stem, the bolt 7 adapted to engage in a socket member 2 as shown in Figure 2. Bolt 7 is normally projected by means of a spring 10 enclosing the stem 8 and engaging said bolt 7 and the outer end of the cylinder 6.

A shaft 11 is journaled in the member 5 and has an arm 12 secured thereto and engaging in slot 9. When the hinge member 5 is installed on the storm sash B, a threaded bushing 13 engages the upper stile of the sash, as shown, and forms a journal for the shaft 11. Secured to the inner end of the shaft 11 is a lever 14 and provides for manipulation of the bolt 7 from the inside of the building. When the storm sash is in the position shown in the drawings, and it is desired to remove the storm sash, it will be apparent that by pressing the lever 14 downwardly, the arm 12 will be moved away from the cylinder 6 and because of its engagement in the slot 9 in the stem 8, the bolt 7 will be withdrawn from the socket 2. This will enable the operator to move the sash B outwardly of the window frame A and the stud 4 may then be released from engagement with the other socket 2 and the sash may then be taken into the building through the window. By reversing the operation, the storm sash may be installed by manipulation from the interior of the building.

What is claimed is:—

A hinge comprising two members, one of said members including a socket, a cylinder on the other member, a cylindrical bolt in said cylinder and adapted to engage in said socket, a stem on said bolt and having a longitudinal slot, a spring enclosing the stem and normally tending to project the bolt, a shaft journaled on the last mentioned member, an arm secured to said shaft and engaging in the slot, and a lever secured to the shaft, said arm by directly engaging said bolt providing means to project and retract it.

In testimony whereof I affix my signature.

FRED JACHIMSTAL.
